US0D1097202S

(12) **United States Design Patent** (10) Patent No.: **US D1,097,202 S**
(45) Date of Patent: ** Oct. 7, 2025

(54) **BUILDING**

(71) Applicant: **Apple Inc.**, Cupertino, CA (US)

(72) Inventors: **Christopher Daniel Peak**, Oakland, CA (US); **Jonathan P. Siegel**, San Francisco, CA (US); **Christopher M. Green**, Woodside, CA (US); **David Nelson**, London (GB); **Stefan Behling**, London (GB); **David Summerfield**, London (GB); **James McGrath**, Cupertino, CA (US); **Peter Han**, Ridgewood, NJ (US); **Adrian Parkinson**, London (GB)

(73) Assignee: **Apple Inc.**, Cupertino, CA (US)

(**) Term: **15 Years**

(21) Appl. No.: **29/832,800**

(22) Filed: **Mar. 30, 2022**

Related U.S. Application Data

(63) Continuation of application No. 29/798,975, filed on Jul. 12, 2021, now Pat. No. Des. 950,103, which is a continuation of application No. 29/680,431, filed on Feb. 15, 2019, now Pat. No. Des. 927,729, which is a continuation of application No. 29/617,035, filed on Sep. 11, 2017, now Pat. No. Des. 841,189, which is a continuation of application No. 29/553,504, filed on Feb. 2, 2016, now Pat. No. Des. 797,305.

(57) **CLAIM**

The ornamental design for a building as shown and described.

DESCRIPTION

FIG. 1 is a top front perspective view of a building showing the claimed design;

FIG. 2 is a front view thereof;

FIG. 3 is a left side view thereof; and,

FIG. 4 is a right side view thereof.

The dashed broken lines in the figures show portions of the building that form no part of the claimed design.

The oblique shade lines in the figures show transparency or translucency.

1 Claim, 4 Drawing Sheets
